UNITED STATES PATENT OFFICE.

LUDWIG L. BLAKE, OF SOUTH BEND, INDIANA.

CLAMP.

1,262,300.

Specification of Letters Patent.

Patented Apr. 9, 1918.

Application filed November 17, 1916. Serial No. 131,923.

To all whom it may concern:

Be it known that I, LUDWIG L. BLAKE, a citizen of the United States, residing at South Bend, in the county of St. Joseph and State of Indiana, have invented certain new and useful Improvements in Clamps, of which the following is a specification.

The invention relates to an improvement in clamps contemplated for a specific purpose, and constructed with a view to permit its being secured in clamping adjustment against the possibility of release, except through the use of an implement constructed for particular coöperation with the specific clamp.

The clamp of the present invention is designed particularly for use as the securing member in fixing automobile trunks or similar receptacles to the running board of vehicles, the clamp being designed for use in connection with any one of a number of trunk formations, such for example as shown in my copending applications, Serial Numbers 122,051 and 131,924, filed Sept. 25, 1916, and Nov. 17, 1916, respectively.

In such use, the clamp should be specifically constructed so as to be released by a particular tool or key, and such key and specific clamp should be so relatively formed that only the particular key will be capable of co-action with the clamp to operate the same to release the clamping action thereof on the running board. Under these conditions, the clamps when set are held against the possibility of unauthorized tampering to free the trunk, and in a general sense, may be said to be locked in applied positions and releasable only through the use of the particular key designed for that clamp.

The invention in the preferred form of details will be described in the following specification, reference being had particularly to the accompanying drawings, in which:—

Figure 1 is a view in side elevation, showing the clamp in applied position;

Fig. 2 is an enlarged vertical section illustrating the adjustable member of the clamp in place, and showing the construction of such member with a view to preventing its

manipulation except through the use of a proper key;

Fig. 3 is a bottom plan of the same; and 55

Fig. 4 is a detail view of the wrench or other key for the particular clamp.

The clamp illustrated which may, of course, be constructed of any appropriate material, and in any desired size or sizes, 60 involves, for the purpose of the present invention, a body 1, having upper and lower arms 2 and 3, which are adapted to partly embrace the running board 4 of the vehicle or other fixture. The free end of the arm 2, constituting the nose of the clamp, is shown in the present instance, as presenting a bearing surface or plate 5 disposed on a plane below the plane of the bottom of the main length of the arm, such plate being of a size and shape to fit in a recess or socket in the bearing bracket designated generally at 6. This bracket forms the subject matter of a separate application above referred to, and hence is indicated herein 75 merely as a means carried by the trunk with which the nose end of the clamp is adapted to coöperate. The trunk carried means for coöperation with the clamp may, of course, so far as the present invention is concerned, 80 be considered or arranged in any desired manner, and if it is further essential, the nose end of the clamp may have any desired specific construction to coöperate with the trunk carried means.

The present invention deals more particularly with the adjustable member through the medium of which the clamping function of the clamp is secured. The free end of the arm 3 is formed with a sleeve-like extension 7 disposed at right angles to the general plane of the arm, the bore of the sleeve extending longitudinally thereof, and for an appreciable distance about centrally of the length of the sleeve, the wall of the 95 bore is interiorly threaded as at 8. The wall of the bore, below the threaded portion, is of somewhat greater diameter than said threaded portion, and plain as at 9. Above the threaded portion the bore is enlarged, with the wall following a compound curve of gradually increasing diameter, this enlarged portion forming what may be termed a seat 10.

Mounted for threaded adjustment in the bore of the sleeve, is a stem 11, which for the greater portion of its length, is threaded as at 12, for coöperation with the threaded portion 8 of the sleeve. The upper portion of the stem 11 is reduced at 13 and rotatably receives a head 14, adapted in the use described, to bear against the lower surface of the running board 4. The head 14 is rotatably mounted on the stem, and a split spring washer 16 is arranged on the stem, encircling the reduced portion thereof, and bearing between the lower surface of the head and the shoulder formed by the reduced portion of the stem.

The relatively lower portion of the stem for an appreciable length thereof, is formed with what may be termed a key-bore 17. The key-bore is preferably of angular contour in cross section, a hexagonal outline being shown. Depending from the top wall of the bore is a positioning element 18, shown in the form of a pin. This positioning pin 18 projects lengthwise the bore, terminating above the lower free end of the stem, and is spaced throughout from the wall of the key-bore. The positioning pin 18 determines the specific locking characteristic of the particular clamp, as it will be at once apparent that the pin may be located in a plurality of distinct positions with relation to the wall of the bore and the center thereof, so that a key or wrench fitting the bore of the clamping member with the pin arranged in one position, would not fit the bore of the clamping member having the pin arranged in another position. Furthermore, it is apparent that the sectional outline of the pin may itself be varied without changing its position, that is, such pin instead of being circular as shown, may be oval, square, or any angular formation, and require a correspondingly shaped socket in the wrench or key to coöperate therewith. Such change in the pin from the form illustrated is, of course, contemplated as a part of the present invention.

The wrench or key illustrated in Fig. 4 is of any appropriate type having a head 19, of a size and shape to snugly fit the key-bore, the head being solid and formed with a recess 20, of a size and shape and of a particular location to properly receive the positioning pin 18 when the wrench is applied. Of course, a wrench other than that formed with the specific limitation noted, could not enter the key-bore and operate the stem to release the clamp member, hence the clamp may be said to be locked against release, except by a proper key.

It is to be particularly noted that the stem of the clamping member is of such length as compared with the sleeve of the clamping arm, that the slightest projection of the head for clamping purposes will carry the lower

end of the stem within the bore of the sleeve. It is, therefore impossible to grasp this end of the clamping member by any wrench or device for retaining the same. Furthermore, the external formation of the clamping head 70 corresponds to the internal formation of the seat 10, which, coupled with the relation of the head, stem, and spring washer, tends to prevent or render extremely difficult, the introduction of a wrench or tool between the 75 head and seat to manipulate the stem of the clamping member from the upper end. This difficulty, primarily incident to the particular formation at this point, is also rendered more pronounced by the fact that the 80 device in its specific use, is beneath the running board of the vehicle, and the lower surface of said bore is so close to the top of the sleeve 7 of the clamp, that a tool could not be introduced for the purpose of operating 85 the stem.

What is claimed is:

1. A clamp including a clamping member arranged for threaded adjustment relative to a fixed part of the clamp, said member being formed with a key-bore, of angular formation and section, and having a positioning pin extending longitudinally of said bore.
2. A clamp having a fixed sleeve interiorly threaded, a clamping member arranged for threaded coöperation with the sleeve, one end of said member being formed with a key-bore having a positioning pin extending longitudinally thereof between the center 100 and wall of said bore.
3. A clamp having a fixed sleeve interiorly threaded, a clamping member arranged for threaded coöperation with the sleeve, one end of said member being formed with a key-bore having a positioning pin extending longitudinally thereof, between the center and wall of said bore, said pin terminating inwardly beyond the free end of the bore.
4. A clamp having the terminal of one arm formed with a head, and a clamping member adjustable in said head and having an operating end adapted to be disposed within the head when the member is in clamping position.
5. A clamp having the terminal of one arm provided with an interiorly threaded sleeve, and a clamping member including a threaded stem for coöperation with said sleeve, said stem having a key receiving formation at one end terminating short of the sleeve end when said member is in clamping position.
6. A clamp having an interiorly threaded sleeve, a clamping member having a stem threaded therein, a head carried by one end of said member, the opposite end of said member being formed with a key-bore of angular formation in plan, for the reception of a particular key, the combined length 130

of the stem and head relative to the length of the sleeve permitting the lower end of the stem to fall short of the sleeve end when the head is in clamping position.

5. 7. A clamp including a clamping member arranged for threaded adjustment relative to a fixed part of the clamp, said member having a key receiving end adapted to be disposed within the body of the clamp when

in clamping position, whereby said end will 10 be inaccessible to manipulating tools other than endwise of the member.

In testimony whereof I affix my signature in presence of two witnesses.

LUDWIG L. BLAKE.
